(57) **CLAIM**

The ornamental design for a metering pump as shown and described.

DESCRIPTION

FIG. 1 is a perspective view of a metering pump showing our new design.

FIG. 2 is a front view of the metering pump of FIG. 1.

FIG. 3 is a rear view of the metering pump of FIG. 1.

FIG. 4 is a left side view of the metering pump of FIG. 1.

FIG. 5 is a right side view of the metering pump of FIG. 1.

FIG. 6 is top view of the metering pump of FIG. 1; and,

FIG. 7 is a bottom view of the metering pump of FIG. 1.

The broken lines depict portions of the metering pump that

form no part of the claimed design.
